(57) **ABSTRACT**

A *Chrysanthemum* plant named 'Zanmupumpkin' characterized by its medium sized blooms with bronze ray florets and prolific branching; natural season flowering date September 23-27 (week 39); blooming for a period of 5 weeks.

3 Drawing Sheets

1

Botanical designation: *Chrysanthemum×morifolium* Ramat.

Cultivar denomination: 'Zanmupumpkin'.

BACKGROUND OF THE INVENTION

The present invention relates to a new and distinct cultivar of *Chrysanthemum* plant, botanically known as *Chrysanthemum×morifolium* Ramat., commercially known as a garden mum, and hereinafter referred to by the cultivar denomination 'Zanmupumpkin'. 'Zanmupumpkin' is a product of a breeding and selection program for outdoor pot mums (garden mums) which had the objective of creating new cultivars with a double type inflorescence, a natural season flower date around week 39, blooming for a period of 5 weeks. 'Zanmupumpkin' is a seedling resulting from a cross of the female parent id 24577 (not patented) with the male parent id 17159 (not patented). Plants of the new cultivar 'Zanmupumpkin' differ from plants of the female parent in the following characteristics. (1). Growth habit. And (2). Natural season flowering date. (1) Plants of the female parent are more compact in shape than those of the seedling. (2). Plants of the female parent flower one week earlier in the season than those of the seedling. Plants of the new cultivar 'Zanmupumpkin' differ from plants of the male parent in ray floret color; the ray florets of the male parent are more salmon colored than those of the seedling.

The new and distinct cultivar was discovered and selected as a flowering plant by Henricus Cornelius Maria Jacobs on a cultivated field in Rijsenhout, The Netherlands in 2008. The first act of asexual production of 'Zanmupumpkin' was accomplished when vegetative cuttings from the initial selection in 2008 were propagated further in a controlled environment in Rijsenhout, The Netherlands. In summer, about 6-8 days are needed to initiate roots in cuttings of the new cultivar, after another 5 days rooted plants are formed. The new culti-

2

var has been found to retain its distinctive characteristics through successive propagations.

BRIEF DESCRIPTION OF THE DRAWINGS

- 5 The present invention of a new and distinct variety of *Chrysanthemum* (of about 18 weeks) is shown in the accompanying drawings, the color being as nearly true as possible with color photographs of this type.
- 10 FIG. 1 shows a plant of the cultivar in full bloom.
- FIG. 2 shows the various stages of bloom of the new cultivar.
- 15 FIG. 3 shows the various stages of foliage of the new cultivar.

DESCRIPTION OF THE INVENTION

The observations and measurements were gathered from plants, in the period of 17 to 24 weeks of age, grown outdoor 20 in Rijsenhout, The Netherlands under natural day length and temperature and planted in week 23 in 2013 (with a warm summer), receiving drip irrigation. The natural blooming date of this crop was September 23-27 (week 39). The average height of the plants was 45 cm. No growth retardants were 25 used. No tests were done on disease or insect resistance or susceptibility. No tests were done on cold or drought tolerance. This new variety produces medium sized blooms with bronze ray florets blooming for a period of 5 weeks.

From the cultivars known to the inventor the most similar 30 existing cultivar in comparison to 'Zanmupumpkin' are 'Zanmuember' (U.S. Plant Pat. No. 23,636) and 'Zanmublast' (U.S. Plant Pat. No. 22,609). When 'Zanmuember', 'Zanmublast' and 'Zanmupumpkin' are being compared the following differences are noticed (1) Natural season flower date. And (2) Plant vigor. (1) Plants of 'Zanmuember' and 'Zanmublast' flower later in the season than those of 'Zanmupumpkin'. (2) Plants of 'Zanmuember' and 'Zanmublast' are less vigorous than those of 'Zanmupumpkin'.

The following is a description of the plant and characteristics that distinguish 'Zanmupumpkin' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum × morifolium</i> Ramat. 'Zanmupumpkin'		
Bud		
Size:	Small; cross-section 6 mm, height 4 mm	
Shape:	Round	
Texture:	Pubescent	
Outside color:	Greyed-green 191A	
Phyllaries		
Number:	21-22, arranged in 3 rows	
Shape:	Elliptic	
Apex:	Acute	
Base:	Truncate	
Margin:	Entire	
Color:	Upper side: Greyed-green 191B Lower side: Greyed-green 189A	
Length and width:	3 mm; 2 mm	
Texture:	Pubescent	
Inflorescences		
Type:	Double	
Height:	1.5 cm	
Diameter:	5-5.5 cm	
Peduncle length:	3-4 cm	
Peduncle color:	Yellow-green 148C	
Peduncle diameter:	1.5 mm	
Peduncle texture:	Pubescent	
Peduncle strength:	Weak	
Number per branch:	About 6-7 inflorescences	
Duration of flowering:	5 weeks	
Seeds:	Produced in small quantities, ovate, Greyed-brown 199A, length 1.5 mm, diameter 0.5 mm; texture: rough with ribs	
Fragrance:	Faint chrysanthemum odor	
Color inflorescences		
Center of inflorescence:	Immature stage: Greyed-Yellow 162B; Mature stage: Greyed-Orange 164 B	
Color of upper side of ray florets:	Greyed-Orange 172B	
Color of lower side of ray florets:	Greyed-Yellow 162B at base to Greyed-Orange 163A at top	
Tonality from distance:	A garden mum with decorative bronze blooms	
Color of ray florets after aging of the plant:	Greyed-orange 163B	
Ray florets		
Type:	Ligulate	
Texture:	Upper and lower side smooth	
Number:	110-120	
Shape:	Elliptic	
Apex:	Dentate	
Base:	Attenuate	
Cross-section:	Flat	
Longitudinal axis:	Straight	
Length of corolla tube:	4 mm	
Diameter corolla tube:	1 mm	
Ray floret margin:	Entire	
Ray floret length:	1.2-2.4 cm	
Ray floret width:	2-5 mm	
Ratio length/width:	High	
Disc florets	Absent	
Receptacle		
Color:	Yellow-green 145D	
Shape:	Domed raised	
Height:	4 mm	
Diameter:	4 mm	
Reproductive Organs		
Androecium:	Absent	
Polle:	Absent	
Gynoecium:	Present on ray florets	
Style color:	Yellow-green 154C	
Style length:	4 mm	
Stigma color:	Yellow 7A	
Stigma width:	1 mm	
Ovary:	Enclosed in calyx; color: Yellow-green 149D	
Plant		
25 Type:	Bushy	
Growth habit:	Spherical shape	
Growth rate:	High	
Height:	45 cm	
Width:	60 cm	
30 Stem color:	Greyed-brown 199A	
Stem strength:	not strong	
Stem brittleness:	Brittle	
Stem anthocyanin coloration:	absent	
Internode length:	1.5-3 cm	
35 Length of lateral branch:	From top to bottom 25-27 cm	
Lateral branch color:	Green 137 C	
Lateral branch, attachment:	Weak	
Lateral branch diameter:	2.5 mm	
40 Lateral branch texture:	Pubescent with ribs	
Branching (average number of lateral branches):	Dense, with 9 breaks after pinching	
Natural season blooming date:	September 23 (week 39) in Rijshenhout, The Netherlands.	
45 Roots-habits:	Fine, freely branching	
Roots-color:	White 155D	
Foliage		
Glossiness:	Leaf upper side: very weak Leaf lower side: absent	
50 Leaf color:	Upper side: Green 138A Lower side: Green 139C	
Color midvein:	Upper side: Yellow-green 147D Lower side: Yellow-green 148D	
55 Size:	Small; length 4.5-8.5 cm, width 2-4 cm	
Quantity (number per lateral branches):	25-30	
Shape:	Elliptic	
60 Texture upper side:	Sparsely pubescent	
Texture under side:	Pubescent	
Venation arrangement:	Palmate	
Shape of margin:	Serrated	
Shape of base of sinus between lateral lobes:	Rounded	

TABLE 1-continued

US PP26,884 P3

5

TABLE 1-continued

Botanical Description of <i>Chrysanthemum × morifolium</i> Ramat. 'Zanmupumpkin'	
Margin of sinus between lateral lobes:	Diverging
Shape of base:	Acute to truncate
Apex:	Mucronulate
Petiole attitude:	Moderately upwards
Petiole length:	1.5-2.5 cm
Petiole diameter:	2-3 mm
Petiole color:	Yellow-green 147D
Stipule:	Small, 1.5 cm

6

TABLE 2

Differences with the comparison variety, when grown under identical conditions			
	'Zanmupumpkin'	'Zanmuember'	'Zanmublast'
Natural season	week 39	week 41	week 40/41
flower date			
Plant height	45 cm	38-40 cm	30 cm

10

I claim:

1. A new and distinct *Chrysanthemum* plant named 'Zanmupumpkin' as described and illustrated.
